NOEL L. ANTHONY, OF CRANSTON, RHODE ISLAND.

ELECTRIC ANNUNCIATOR OR CODE-SIGNALING DEVICE.

1,131,813.

Specification of Letters Patent. Patented Mar. 16, 1915.

Application filed February 2, 1914. Serial No. 815,967.

To all whom it may concern:

Be it known that I, NOEL L. ANTHONY, a citizen of the United States, residing at Cranston, in the county of Providence and State of Rhode Island, have invented certain new and useful Improvements in Electric Annunciators or Code-Signaling Devices, of which the following is a specification.

10 My invention relates to improvements in electric annunciators or call-bell apparatus for sounding code signals at a plurality of distributed points.

15 The object of my improvement is to provide a device of this character which will be of simple construction, less liable to get out of order, and more positive in action than the usual arrangement employed for like purposes.

20 The invention is fully described in the following specification, illustrated by the accompanying drawings, in which like reference characters designate like parts.

In the drawings:—Figure 1 is a plan view 25 of the improved device showing the mechanism contained in the main frame or casing; Fig. 2 is a cross-sectional view of the same taken on the line A—A of Fig. 1, looking in the direction indicated by the 30 arrow a; Fig. 3 is an end view of the apparatus illustrating its electrical connections in circuit with a call-bell and battery; Fig. 4 is a sectional view through the contact-mechanism showing the constructional details thereof.

35 My improved device consists essentially of a flat platen or call-board provided with fixed electrical contacts arranged in series in code order and having a movable contact-member adapted to be traveled across any one of the series; the object being to make and break the electrical circuit to sound the bells or other annunciators in accordance with predetermined signals. The mechanism of the device is operated manually by a suitable hand-lever to shift the movable contact-member to one end of the call-board and, after the indicating-means has been 40 adjusted to the desired signal, the contact-member is drawn across the fixed-contacts by the reverse action of the lever.

45 Referring first to Figs. 1 and 2, B designates the main box or casing in which the operating parts of the device are contained and C is a metal plate secured to its base and 50 adapted to serve as a mounting for the

mechanism. Screwed into the plate C is a stud e on which is pivoted an arm or lever D having a gear D' formed integral with or attached to its hub d'. Pivoted on a stud e 60 is a hand-lever E formed at one end with a toothed quadrant E' adapted to engage the gear D'. The opposite end of the lever E carries a handle e' preferably constructed of vulcanized rubber or some other insulating material to protect the operator from possible electrical shocks.

55 Mounted on the stud e above the arm D are two overlapping arms f, f which constitute the end-members of a usual form of lazy-tongs F. Jointed to the ends of the arms f, f are two intermediate tongs-levers f', f' pivoted together at f³ and having their ends connected with the opposite end-members f², f². The arm D is connected to operate the lazy-tongs F, as later described, by means of the pivot-screw f⁴ in the arm f, which is screwed into its end, see Fig. 2. The pivot-screw f⁵ at the opposite end of the lazy-tongs is screwed into a member 80 g which is formed with a hub g' surrounding a cross-rod G and secured thereto through any suitable means such, for instance, as the pin g². The ends of the rod G are held fixedly in bearings h, h formed 85 on the cylindrical members H, H, which latter are bored to receive two horizontal guiding-rods I, I on which they slide. The side rods or guides I, I are supported at their ends by two metal plates or strips J, J 90 fastened to the ends b, b' of the casing B by suitable screws j, see Figs. 2 and 4. The strips J, J also serve as a support for the fixed-contact platen or call-board K which rests on their edges and is fastened thereto 95 by any suitable means such as the screws k illustrated in Fig. 4.

100 The contact-board K is preferably constructed of hard rubber, fiber or other similar material and serves as a support for the fixed-contacts l, l, etc., while also acting as an insulating medium to separate them electrically from the other parts of the apparatus. The contacts l, l are preferably made in the form of metal studs or plugs mounted 105 in a main backing-plate L, also of metal, which connects all of the series of contacts together electrically and further serves as a means for connecting them in circuit with the battery and bells. The studs l may be 110 soldered to the plate L or driven into holes punched or drilled therein as shown in Fig.

4, being arranged to project through corresponding holes in the insulating-board K. The upwardly projecting ends of the studs *l* are preferably slightly rounded off or con-
 5 vexed to adapt them to allow the spring-pressed plunger or wiper M to pass freely over them.

The wiper M is carried by the movable contact-member N which is arranged as fol-
 10 lows: Extending upwardly from the slide-members H, H are two lugs or arms *h*', *h* in which is mounted a cross-rod G' extending parallel with the rod G above the board K. Mounted to slide on the rod G' is the movable contact-member N which is constructed as shown more particularly in Fig. 4. Its main hub-portion *n* is bored axially at *n*' to receive the rod G' and carries a key *n*² engaging a longitudinal groove 20 or spline *g*³ in the rod to keep it from turning thereon. Projecting horizontally from the hub *n* is an arm *n*³ formed with an axial bore *n*⁴ reaching into the main bore *n*' and opening into a larger counterbore *n*⁵.
 25 Mounted in the bore *n*⁴ is a slidable plug or plunger O formed with a rounded end *o* adapted to engage suitable V-shaped notches or depressions *g*⁴ in the rod G. The plug O is also formed with a head *o*' which
 30 slides in the counterbore *n*⁵ and is engaged by the end of a coiled spring *o*². Fitted to the end of the arm *n*³ is a finger-grip or handle N' which serves as a closure for the end of the counterbore *n*⁵ and against which
 35 the outer end of the spring *o*² bears. The handle N' is preferably made of hard rubber or other insulating-material and may be secured to the member N in any suitable manner, not here shown. Projecting from the opposite side of the hub *n* of the member N is a rectangular extension *n*⁶ provided with a vertical bore *n*⁷ in its under side opening into a larger counterbore *n*⁸ reaching in from its upper side. Mounted
 40 to slide therein is the contact-plunger or wiper M, turned down at *m* to fit the smaller bore *n*⁷ and formed with a head *m*' adapted to the counterbore *n*⁸. The plunger M is also formed with a reduced portion *m*² which passes through a bore *m*³ in a plug *m*⁴ driven into the end of the counterbore *n*⁸. Between the plug *m*⁴ and the head *m*' of the plunger M is a coiled spring *m*⁵ which serves to normally maintain the plunger in
 45 its projected position as illustrated in Fig. 4. Slidably mounted in a cross-bore *n*⁹ of the member *n*⁶ is a detent-pin P having its inner, rounded end adapted to engage a circumferential groove *m*⁶ in the head of the
 50 plunger M. The pin P is operated by a flat spring *p* secured in place on the outside of the member *n*⁶ by the screw *p*'. Normally, the end of the pin P rests on the side of the head *m*' of the plunger M and the latter is free to play up and down in its bore
 55
 60
 65

to a limited extent to allow its end *m* to pass over the ends of the raised contacts *l*. When, however, the plunger M is retracted in its bore beyond the extent required for it to pass over the contacts *l*, the pin P will 70 be pressed down by its spring *p* to cause its end to engage the groove *m*⁶ to retain the plunger in its retracted position. The purpose of this locking- or detent-means for the plunger M is to provide that when the 75 device is being set, that is, when the contact-member N is first passed across the board K, it will not act to make contact with the studs *l* to ring the calls. In other words, the contact-member N is moved to one end of the 80 board before setting it to ring the desired call and during this time the plunger M must be held out of its operative position in order not to allow it to engage the wrong series of contacts. 85

The arrangement for operating the detent-means for the plunger M is as follows: Extending across the board K beyond the last, upper line of contacts *l*, is a strip R formed with a beveled face *r*, see Fig. 2. 90 The face *r* of the strip R is adapted to engage the lower end *m* of the plunger M after the member N has been carried across all of the contacts. When this engagement takes place the plunger M is forced into its 95 retracted position where it is held by the detent-pin P until released. For releasing the plunger M from its detent I employ a similar strip S at the lower end of the case B, preferably fastened to the cover *b*². The 100 strip S has a beveled face *s* which acts against the top of the plunger M as shown in Figs. 2 and 4. The end of the detent-pin P being rounded off and the groove *m*⁶ in the plunger M being relatively shallow, 105 the plunger M can be forced free of the pin P with only a very slight resistance.

The contact-member N is carried across the contact-board K through the operation of the lazy-tongs F which is energized from 110 the arm D. The arm D is moved through its gear connection with the hand-lever E, which latter could be operated manually in either direction, but is preferably controlled by a spring T. One end of the spring T is 115 hooked into a hole *e*² in the lever E and its opposite end is fastened to a pin or screw *t* secured in the plate C, see Figs. 1 and 2. I have here illustrated the spring T as adapted to move the lever E in the direction indicated by the arrow *x*, Fig. 1, and a stop-pin *c*³ secured in the base of the casing B serves to limit its movement in this direction. 120

The spring T causes the lever E to retract 125 the lazy-tongs into its closed position shown by the dash lines in Fig. 1, but the arrangement of these parts could be reversed if desired. With this arrangement the lever E is moved manually in the opposite direction 130

to extend the tongs to the position shown by full lines in Fig. 1, and it is desirable to accomplish this movement quickly. When the tongs is retracted, however, to draw the 5 contact-plunger across the studs l and effect the sounding of the signals, it is necessary that the contact-member N should have a relatively slow movement in order that the ringing of the bells shall take place during 10 an extended period. To provide for this I employ a governor-device for controlling the spring-actuated movement of the lever E which is arranged as follows: Pivotally fastened to the lever E by the stud u is a rack- 15 bar U formed with gear-teeth u' on one of its sides. The teeth u' mesh with a pinion V mounted rotatably on a stud v screwed into the plate C . A roll u^2 held on a screw u^3 bears against the opposite side of the 20 rack u to hold it in engagement with the gear V , there being enough clearance between the two to allow for the tilting movement of the rack as the lever E swings on its pivot. Referring to Fig. 2, the pinion V 25 has its hub v' formed with ratchet-teeth v^2 which are adapted to engage oppositely-arranged teeth v^3 on the hub v^4 of a gear V' . The gear V' is also mounted rotatably on the stud v and is adapted to slide axially thereof 30 to release its teeth v^3 from the teeth v^2 of the pinion V . A relatively light, spider-like spring v^5 , not shown in Fig. 1, is mounted on the stud v between its head and the face 35 of the gear V and acts against the latter to normally maintain the ratchet-teeth v^2 , v^3 in engagement. The gear V' meshes with a pinion W which is formed as a part of or attached rotatively to a gear W' mounted to turn on a stud w . The gear W' meshes with 40 a pinion W^2 fast with a gear W^3 rotatable on a stud w' , and the gear W^3 , in turn, meshes with a pinion W^4 mounted on the stud w^2 . The purpose of this train of gearing $V'-W'$, above described, is to retard 45 the movement of the lever E under the action of its spring T and any other suitable mechanism might be substituted in its place. For instance, a friction-band operating 50 against a drum during its rotation in one direction and free therefrom during the opposite rotation would effect the same purpose. Again, if desired, several of the gears of the train in the present arrangement could be dispensed with and adjustable fan- 55 blades applied to the main gear V' to serve the same purpose of retarding the motion of the parts.

Referring to Figs. 1 and 3, I have illustrated the fixed-contacts on the call-board K arranged in twenty rows so that a like number of different calls can be given on the 60 bells which are distributed at different points in the store or building where the device is in use. The plugs or contacts l may be arranged in any order or sequence in each row,

according to the code decided upon, and Fig. 1 shows six different arrangements. In the last or twentieth row, for instance, there are five contacts arranged at equal intervals, then a longer space intervenes and 70 there is a sequence of four contacts spaced equidistantly. After the four contacts, a still longer space intervenes, and then the code is repeated with five and four again making the call five rings and then four, or 75 fifty-four as it might be designated. On the fifteenth row, as here shown, the contacts are arranged with first a series of four then a series of three, repeating with longer intervals between each two signals. 80

Referring to Figs. 2 and 3, it will be observed that the end b' of the casing B is formed with an opening b^3 through which the finger-lever N' projects when the contact-member N is carried to the lower end 85 of the call-board K . Along the upper edge of this opening is a series of indices b^4 numbered from one to twenty. These register with the rows of plugs l having the individual code arrangement above explained, and 90 the notches g^4 in the rod G' also correspond therewith. Through this arrangement the contact-member N can be set for engagement with the contacts of any desired signal code and the plunger-plug O in the member N 95 acts to engage the proper notch g^4 to hold it in position on the rod G' during its traverse over the ends of the contacts. Referring to Fig. 3, the backing-plate L in which the contacts l are mounted is connected by a 100 wire y to a binding-post Y secured in the side b^5 of the casing B . A second binding-post Y' is connected by the wire y' to the end plate or strip J which supports the ends of the rods I , I . Since the members H , H 105 which carry the rods G , G' and slide on the rods I , I are of metal, the contact-member N mounted on the rod G' will be electrically connected to the binding-post Y' . From the binding-post Y a wire z extends to the 110 bell Z and a second wire z' leads from the binding-post Y' to one pole of a battery X , while from the other pole thereof a wire z^2 leads to the bell Z . In place of the battery X here symbolically illustrated any other 115 suitable source of electricity can be employed, and while I have only shown one bell Z it will be understood that usually a plurality of the same or other sounding devices are arranged within the circuit. 120

The operation of the complete device is as follows: My new device is designed particularly for use in stores, offices, hotels, counting-rooms, factories, or for any other building where it is desired to send out 125 calls from a central station to distributed points. For instance, in the case of stores having a large number of employees, it is desirable to have some means for calling to the office or other central point the vari- 130

ous clerks in the different departments. The main apparatus comprised in the casing B is installed at the office or any other convenient location and is connected by wires to the bells or similar sounding-devices which are in circuit with a suitable source of electricity such as the usual battery X. When it is required to send out a call for any certain individual the operator first moves the hand-lever E to the position illustrated in Fig. 1. The lever E acts through the quadrant E' and gear D' to swing the arm D and extend the lazy-tongs F to the position illustrated by full lines in Fig. 1. While the lever E is being thus operated manually its attached rack-bar U will rotate the gear V, but the gear V' will remain idle. That is to say, the friction of the gears in the train V'—W⁴ will be greater than the resistance of the spring v⁵ which holds the ratchets v² and v³ in engagement and hence the gear V will rotate free from the gear V'. This allows the lever E to be operated with a comparatively free movement, the only resistance being that of the spring T, and hence the lazy-tongs F can be extended very quickly. This extension of the lazy-tongs causes the rods G, G' which carry the contact-member N to move toward the lower end of the call-board K while the supports H, H slide on their guiding-rods I, I. During this movement of the contact-member N across the board the spring-plunger M is withheld by its detent-pin P from engagement with the fixed contacts l until the handle N' is carried through the opening b³ in the end of the casing in convenient position to be grasped by the operator's other hand. Now, say, for instance, clerk number twenty, who answers to the call fifty-four is to be called, then the operator will slide the contact-member N to the last index numbered in accordance, as shown in Figs. 1 and 3. After the contact-member N is thus adjusted it will be retained in its proper position on the rod G' by the detent-plunger O which engages the appropriate notch g⁴ in the rod. Meanwhile the upper end of the plunger M has been engaged by the beveled face s of the strip S to release it from the detent-pin P, and the spring m⁵ will have caused it to be projected downwardly into position for its lower end to wipe across the contact-plugs l, see Fig. 4.

The device is now set for operation and its further action is entirely automatic. The operator merely releases the handle e' and the spring T will then act to swing the lever E in the direction indicated by the arrow x, Fig. 1. This causes the lazy-tongs F to be contracted or drawn together and the contact-member N will be drawn up across the board K. As the member N passes over the row of contacts with which

its plunger M is in alignment, the end of the latter will wipe across the contact-plugs l and make and break the electrical circuit at intervals as arranged. As before stated, this active movement of the contact-member 70 is regulated by the governor-device comprising the gear-train V'—W⁴. That is to say, the gears V, V' will be held in engagement through the ratchet-teeth v², v³ and hence the whole train of gears must be turned 75 from the movement of the rack-bar U. The friction of the gears will cause a retardation in the movement of the lever E which controls the lazy-tongs F and therefore the contact-member N will be moved quite 80 slowly. In this way the contact-plunger or wiper M is caused to make contact with each stud l during a relatively extended period and therefore the bells will be rung with the required intervals of sound and silence. 85 After the contact-member N has been passed over all of the fixed-contacts in one row its plunger M will ride up on the beveled strip R and be carried into its retracted position to be held by the detent-pin P again. In 90 this way the plunger M is withheld from engagement with the contact-stud l until the member N is again carried to the opposite end of the call-board K.

It will be seen that my new invention provides an efficient device for the purpose specified without requiring the usual complicated arrangement of clock-motors or other operating mechanism. In most apparatus of this sort it is necessary to wind 100 up a spring-motor or to drive the mechanism from some other source of power whereas with my improvement the mechanism is practically automatic and only requires a simple movement of the hand-lever. 105 My new device is therefore more positive in action and less liable to get out of order and far less expensive to manufacture.

Various modifications might be made in the form and structure of the parts of my 110 device without departing from the spirit or scope of the invention.

Therefore, without limiting myself to the exact construction shown and described, 115 what I claim is:—

1. In an electric signaling-device, the combination with a plurality of series of fixed-contacts arranged in code order, of a movable contact-member, and manually-controlled mechanically-actuated means for operating the movable contact-member to draw it across any one of the series of fixed-contacts. 120

2. In an electric signaling-device, the combination with a plurality of fixed-contacts 125 arranged in rows in code order, of a movable contact-member adapted to be drawn across the different rows of fixed-contacts, a lazy-tongs for moving said contact-member, and a hand-lever for operating the lazy-tongs. 130

3. In an electric signaling-device, the combination with a plurality of rows of fixed-contacts arranged in code order in a common plane, of a movable contact-member, a hand-lever for operating said contact-member to draw it across any one of the rows of fixed-contacts, and a spring for controlling the operation of the hand-lever.

4. In an automatic code-signaling device, the combination with a plurality of rows of fixed-contacts spaced at intervals in code order, of a movable contact-member, means for adjusting said contact-member in relation to the different rows of fixed-contacts, and a hand-lever for operating the contact-member to cause it to be drawn across the fixed-contacts.

5. In an electric code-signaling device, the combination with a plurality of rows of fixed-contacts arranged in code order, of a movable contact-member, means whereby said contact-member may be moved across any one row of the fixed-contacts, a hand-lever for operating the contact-member to move it across the fixed-contacts in one direction, and a spring for operating the hand-lever to move the contact-member across the fixed-contacts in the opposite direction.

30 6. In an electric code-signaling device, the combination with a plurality of rows of fixed-contacts arranged in code order, of a movable contact-member, means whereby said contact-member may be adjusted into alignment with any one of the rows of fixed-contacts, manually-controlled means for moving the contact-member across any one of the rows of fixed-contacts, and a governor-mechanism for controlling the speed of movement of the contact-member to regulate the timing of its engagement with the individual fixed-contacts.

7. In an electric code-signaling device, the combination with a plurality of rows of fixed-contacts arranged in code order, of a movable contact-member, means whereby said contact-member may be adjusted into alignment with the different rows of fixed-contacts, means for drawing said contact-member across any one of the rows of fixed-contacts, a spring for operating said means, and a governor-mechanism for controlling the movement of the contact-member under action of the spring to regulate the timing of its engagement with the fixed-contacts.

8. In an electric code-signaling device, the combination with a plurality of rows of fixed-contacts arranged in code order, of a movable contact-member, means for adjusting said contact-member in relation to the rows of fixed-contacts, manually-operated means for moving the contact-member across the different rows of fixed contacts in one direction, a spring for moving the contact-member across the fixed-contacts in the op-

posite direction, and a governor-mechanism for controlling the speed of movement of the contact-member under action of the spring to regulate the timing of its engagement with the individual fixed-contacts.

9. In an electric code-signaling device, the combination with a plurality of rows of fixed-contacts arranged in code order, of a movable contact-member, means for adjusting said contact-member into alignment with the different rows of fixed-contacts, manually-operated means for moving the contact-member across the fixed-contacts in one direction, detent-means for preventing contact between the contact-member and the fixed-contacts during its movement by the manual-means, means for releasing the detent-means, and a spring to move the contact-member across the fixed-contacts in the opposite direction to cause engagement therebetween.

10. In an electric signaling-device, the combination with a plurality of series of fixed-contacts arranged in code order, of a movable contact-member adapted to be drawn across any one of the series, means for drawing the contact-member across the different series of fixed-contacts, a wiper carried by said contact-member and adapted to engage the fixed-contacts, detent-means for withholding the wiper from engagement with the fixed-contacts during the movement of the contact-member in one direction, and means to release the detent-means to allow engagement of the wiper with the contacts during the movement of the contact-member in the opposite direction.

11. In an electric signaling-device, the combination with a casing, of a call-board inclosed by said casing, a plurality of fixed-contacts arranged in rows in code order on the call-board, a movable contact-member, means for adjusting said contact-member into alignment with the individual rows of fixed-contacts, and manually-controlled means for drawing said contact-member across the contacts.

12. In an electric signaling-device, the combination with a call-board, of a plurality of rows of spaced-apart fixed-contacts arranged in series on said board, a movable contact-member, means for adjusting said contact-member into position to engage any one of the series of fixed-contacts, and manually-controlled means for drawing said contact-member across the board to cause it to engage with the fixed-contacts of the different series.

13. In an electric signaling-device, the combination with a call-board, of a plurality of spaced-apart contacts fixed on said board and arranged in series in code order, a movable contact-member, means for adjusting said contact-member into position to engage any one of the series of fixed-contacts, man-

ually-controlled means for operating said contact-member to draw it across the board, and means to govern the movement of the contact-member to regulate the intervals of engagement between the latter and the fixed-contacts.

14. In an electric signaling-device, the combination with a call-board having a plurality of contact-plugs thereon arranged in 10 rows in code order, of a slidable contact-member adjustable laterally of said call-board, means to adjust said contact-member into alinement with any one of the rows of contact-plugs, means to slide the contact-member along the rows of contact-plugs, a wiper carried by said contact-member to engage the contact-plugs, and means to render said wiper mechanism inoperative during the movement of the contact-member 15 in one direction.

15. In an electric signaling-device, the combination with a metal plate having a plurality of raised contacts arranged thereon in rows in code order, of a slidable contact-member, means for adjusting said contact-member into alinement with the different rows of fixed-contacts, manually-controlled means for sliding the contact-member along the rows of fixed-contacts, a wiper 20 adapted to wipe across the individual fixed-contacts, and means to render the wiper inoperative during the movement of the contact-member in one direction.

16. In an electric signaling-device, the combination with a call-board having a plurality of fixed-contacts arranged in rows in 35 code order, guide-rods arranged parallel with the sides of the call-board, a cross-rod arranged above the call-board, slide-members supporting the cross-rod and adapted to slide on the guide-rods, a contact-member adjustable along the cross-rod, and means on said contact-member for engaging the fixed-contacts when the cross-40 rod is slid longitudinally of the guide-rods.

17. In an electric signaling-device, the combination with a call-board having a plurality of fixed-contacts arranged in rows in 45 code order, of a cross-rod arranged above the call-board, guiding-means to adapt the cross-rod to slide in parallel relation to the

call-board, a contact-member adjustable longitudinally of the cross-rod, detent-means to maintain the contact-member in appropriate relation to the individual rows of 55 fixed-contacts, and means to slide the cross-rod.

18. In an electric signaling-device, the combination with a call-board having a plurality of fixed-contacts arranged in rows in 60 code order, of a member slidable above the face of the call-board, a contact-member adjustable on said sliding-member to adapt it to engage the different rows of fixed-contacts, a lazy-tongs connected to operate the 65 sliding-member, a hand-lever for actuating the lazy-tongs, and a spring for operating said lever.

19. In an electric signaling-device, the combination with a call-board having a plurality of fixed-contacts arranged in rows in 70 code order, of a contact member slidable across the different rows of fixed-contacts, means whereby said contact-member can engage the fixed-contacts when moving in one 75 direction only, a lazy-tongs for sliding the contact-member, a lever for operating the lazy-tongs, a spring for moving the lever in one direction, and a speed-governing device adapted to be driven from the lever 80 when the latter is moved by its spring but free therefrom when the lever is moved in the opposite direction.

20. In an electric signaling-device, the combination with a series of fixed-contacts, 85 of a contact-member slidable along the same, a spring-pressed plunger adapted to be normally projected into position to engage the fixed-contacts, a spring for operating the plunger, means to engage the plunger to retract it from its position of engagement with the fixed-contacts, detent-means to retain the plunger in its retracted position, and means to release the detent to allow the 90 projection of the plunger into operative position.

In testimony whereof I affix my signature in presence of two witnesses.

NOEL L. ANTHONY.
